INVENTOR.

UNITED STATES PATENT OFFICE.

LEONCE L. BATTU, OF NEW YORK, N. Y., ASSIGNOR TO SLAG STEAM GENERATOR COMPANY, OF NEW YORK, N. Y., A CORPORATION OF DELAWARE.

SLAG STEAM-GENERATOR.

1,135,984.

Specification of Letters Patent. Patented Apr. 20, 1915.

Application filed January 9, 1915. Serial No. 1,300.

To all whom it may concern:

Be it known that I, LEONCE L. BATTU, a citizen of the United States, whose post-office address is 90 West street, New York 5 city and State, have invented certain new and useful Improvements in Slag Steam-Generators, which improvements are fully set forth in the annexed specifications.

My invention has for its object improved 10 means through which the heat contained in molten slag is absorbed by a fluid, said fluid being in turn cooled by the circulation in its mass of an independent supply of secondary fluid, which secondary fluid is kept cool by 15 evaporation. I heat the primary fluid by direct contact with the slag and at the same time I cool the primary fluid by circulating a secondary fluid in pipes or ducts located in the mass of the primary fluid. The sec- 20 ondary fluid is circulated from an evaporat- ing tank into the pipes or ducts contained in the mass of the primary fluid in such a way that when the secondary fluid flows into 25 the pipes or ducts contained in the mass of the primary fluid it is heated by absorption of heat from the primary fluid and then is brought back into the evaporator where it is subjected to a diminishing pressure, which has a cooling influence on said secondary 30 fluid.

The accompanying drawing shows a vertical cross section through an apparatus embodying my invention.

In the figure A is a container in which a 35 mass of fluid, 20, is placed.

1 is an opening through which slag is poured into fluid 20.

C is a duct in which the slag and fluid 20 are mixed. The slag falls to the bottom of 40 container A and the liquid separated from the slag, but heated by slag, is circulated around the casing of the duct C.

P is a source of additional fluid. When 45 float 3 falls below a predetermined level, link 4 operates valve 2 and additional fluid enters into container A through pipe 14.

S is a screw conveyer for the slag which enters opening 12 of the screw and is discharged at opening 13.

50 B is an evaporating chamber, in which is contained a mass of fluid, 21. This fluid, through opening 23, is made to circulate through coil pipe E, which coil pipe E is located in the fluid of container A. Pump 55 F, connected to coil E, pushes back the

fluid through opening 24 in evaporating chamber B. Float 7, through link 6, actuates valve 5, which opens pipe 15 and allows additional fluid to flow from source R into evaporating chamber B, when the fluid in 60 evaporating chamber B is lower than a pre-determined level.

8 is a pipe connected to a power engine O.

9 is a pipe leading the fluid which has passed through engine O into cooling ap- 65 paratus M.

H is a pump which handles the fluid cooled in M through pipe 11 into evaporating chamber B.

In practising my invention, I heat fluid 20 70 of container A by pouring slag or other molten material through duct C. It will also be seen that I circulate the fluid over coil pipes E, thus facilitating the interchange of temperature between fluid 20 and 75 fluid 21. The heat absorbed by fluid 21 through its being circulated by pump F through coil pipes E is liberated by evaporation due to cooling apparatus M. The cooling apparatus M can be a standard con- 80 denser or any other type of apparatus in which heat is absorbed.

I do not wish to be restricted to the inter- 85 position of a power apparatus between pipes 8 and 9, as the heat contained in the evap- orated fluid 21 may be used in cooling ap- paratus M, which in this instance may be an electrolytic tank, in which the heat contained in the evaporated fluid 21 will be used to heat the bath. It may be useful to use 90 the fluid cooled in M over and over again and for this reason I have shown pump H, which handles this cooled fluid and sends it back into evaporator B. The source of additional fluid P and R may be water, for 95 instance, but they can also be different fluids, such as water for P and alcohol for R. Power engine O may be an elastic fluid turbine.

By means of my invention I provide an 100 indirect method of heating a fluid. I first transfer the heat of the slag or other molten material to a fluid and I extract from this fluid the heat imparted to it by the slag by 105 circulating the secondary fluid in the mass of the primary fluid. If the slag or molten material contains impurities, it will be seen that these impurities will not affect fluid 21, as this fluid is circulated in a closed cir- 110 cuit. It will also be seen that I have pro-

vided means to use over and over again fluid 21 and that additional fluid from source R would only be provided to take care of leaks. I have also provided means to use two different fluids, which fluids may have widely varying boiling points when submitted to the same pressure. It will also be seen that fluid 21 may be a liquid, a gas or a vapor.

I do not wish to be limited to slag and 10 this word is used in the following claims as meaning broadly slag itself and any other preheated material.

Having thus described my invention, I claim as new:

15 1. In a slag steam generator means to transfer the heat contained in the slag to a primary fluid, means to transfer the heat absorbed from the slag by the primary fluid to a secondary fluid and means to cool the secondary fluid.

2. In a slag steam generator means to transfer the heat contained in the slag to a primary fluid through mixing the slag and the primary fluid, means to transfer heat 25 from the primary fluid into the secondary fluid and means to cool the secondary fluid.

3. In a slag steam generator means to transfer the heat contained in the slag to a primary fluid, means to circulate a secondary fluid through the primary fluid and means to cool the secondary fluid.

4. In a slag steam generator means to mix slag and a primary fluid, means to circulate the primary fluid, means to circulate 35 a secondary fluid through the primary fluid and means to cool the secondary fluid.

5. In a slag steam generator a container for a primary fluid, means to circulate the primary fluid in said container, means to 40 separate the slag from the primary fluid, and a duct or piping to circulate a secondary fluid through the primary fluid.

6. In a slag steam generator, a container for a primary fluid, circulating means for 45 the primary fluid, an evaporating chamber containing a secondary fluid, means to circulate the secondary fluid through the primary fluid and means to cool the secondary fluid.

7. In a slag steam generator means to absorb heat from slag through direct contact of a primary fluid and the slag and means to circulate through the primary fluid a secondary fluid, means to cool the secondary fluid and means to add supplemental 55 primary fluid.

8. In a slag steam generator means to absorb heat from slag through direct contact of the slag and a primary fluid, means to circulate a secondary fluid through the primary fluid, means to cool the secondary fluid and means to add supplemental secondary fluid.

9. In a slag steam generator means to absorb heat from slag through direct contact of the slag and a primary fluid and means to circulate a secondary fluid, having a lower boiling point than the primary fluid, through said primary fluid.

10. In a slag steam generator a container 70 for a primary fluid, means to mix the primary fluid and the slag, means to circulate a secondary fluid through the primary fluid, a cooling apparatus adapted to absorb the heat from the secondary fluid and means to circulate the cooled secondary fluid discharged from the cooling apparatus through the primary fluid.

11. In a slag steam generator a container for a primary fluid, means to introduce slag 80 into the container, a duct or piping to circulate a secondary fluid through the primary fluid, means to cool the secondary fluid by evaporation and means to return the secondary fluid after evaporation 85 through the primary fluid.

12. In a slag steam generator a primary fluid, a secondary fluid, means to transfer heat from the slag to the primary fluid and means to transfer the heat absorbed by 90 the primary fluid to the secondary fluid.

In witness whereof I have hereunto subscribed my name this 8th day of January, 1915.

LEONCE L. BATTU.
